(74) Attorney, Agent, or Firm — Craft Chu PLLC;
Andrew W. Chu(57) **CLAIM**

The ornamental design for a raking device, as shown and described.

DESCRIPTION

FIG. 1 is an upper perspective view of the raking device showing my design.

FIG. 2 is front elevation view thereof;

FIG. 3 is a back elevation view thereof;

FIG. 4 is a side elevation view thereof;

FIG. 5 is an opposite side elevation view thereof;

FIG. 6 is a top plan view thereof;

FIG. 7 is a bottom plan view thereof;

FIG. 8 is another upper perspective view thereof, showing another raking device in broken lines; and

FIG. 9 is a rear perspective view thereof, showing a guide rail in broken lines as attached to one side; and,

FIG. 10 is another rear perspective view thereof, showing another guide rail in broken lines as attached to another side. The portions in broken lines indicate environment and form no part of the claimed design.
